UNITED STATES PATENT OFFICE.

FRANK AMOS, OF WHEELING, WEST VIRGINIA, ASSIGNOR TO WHEELING TILE COMPANY, OF WHEELING, WEST VIRGINIA, A CORPORATION OF WEST VIRGINIA.

INSULATOR.

1,311,483.

Specification of Letters Patent. Patented July 29, 1919.

Application filed November 28, 1917. Serial No. 204,424.

To all whom it may concern:

Be it known that I, FRANK AMOS, a citizen of the United States, residing at Wheeling, in the county of Ohio and State 5 of West Virginia, have invented a certain new and useful Improvement in Insulators, of which the following is a specification.

This invention pertains to insulators and relates more particularly to that type where- 10 in a base and cap piece are employed to hold and clamp one or more wires between them when the parts or elements are in juxtaposition and secured together and in place by a screw or nail.

15 The main object of the invention is to produce an insulator easy of manufacture and which at the same time will effectively hold the wires in place.

20 A further object of the invention resides in so constructing the members of the insulator that the wire will be firmly clamped and any strain or pull exerted on the wire will tend to make the retaining elements of the members more tightly grip or bind the 25 wire in place.

A still further object is to provide a head or cap piece which is symmetrical in form and may, therefore, be placed in clamping relation to the base and wire or wires without 30 the necessity of bringing such head into a particular relationship with the underlying wire-receiving grooves in the base.

With these and other objects in view, a 35 description of the insulator will be given, reference being had to the annexed drawings, wherein:

Figure 1 is a perspective view of the base and head, the under face of the latter being exposed and partly broken away;

40 Fig. 2 a vertical sectional view of the base and head, the plane of section of the base being indicated by the line II—II of Fig. 1;

Fig. 3 a similar view of the base, the plane 45 of section being on the line III—III of Fig. 1; and

Fig. 4 a sectional elevation of the base and cap.

The parts will preferably be formed of 50 porcelain or other suitable dielectric material, which may be readily molded and will afford requisite strength.

The base, denoted by 1, will preferably be cylindrical in form and provided on its 55 upper end or face 2 with a centrally-dis-

posed stud or teat 3 and two parallel grooves or channels 4, 4, the outer ends of which are given a slight downward inclination, as best shown in Fig. 3. A series of transverse or cross ribs 5 is provided in the bottom of each 60 groove, the ribs being narrow or presenting a comparatively sharp upper edge, as will be best seen upon reference to Fig. 3.

The cap or head piece, denoted by 6, is circular in outline, and is provided with a 65 central socket or recess 7, a circumferentially-disposed depending narrow rim 8, and a series of radially-disposed ribs 9, extending inwardly from the rim to the recess or socket 7, of a size to receive the stud 3. 70

The head and base are provided with alining bores 10 and 11, as is usual, and through which the fastening element, as a nail or screw, may be passed.

The lower end of the base will preferably 75 be hollowed out to save material, and lighten the device, and to likewise produce an annular rim 12, which assists the structure in more readily finding a bearing on the surface to which it is secured than would be 80 the case if the under surface were flat and unbroken.

The diameter of the cap and body is preferably the same, and the lug or teat 3 is 85 rounded except where it is cut away or reduced by the formation of the cross-grooves 4; consequently, the lug entering the recess 7 centers the head or cap, and the flange or rim 8 bears upon or overlies the upper face 2 of the body 1. This permits of the placement 90 of the cap on the body without the necessity of bringing the parts to any definite position or adjustment.

By reason of the radial arrangement of the ribs 9 and the transverse disposition of the ribs 5, the two series of ribs will, in whole or in part, stand at an angle to each other, it being, of course, possible under one position to have one of the ribs 9 to each side of the socket 7 parallel to the rib 6 in 95 the underlying grooves 4. The remaining ribs 9 will, however, have an angular relation to the ribs 5.

In order to permit of the placement of the cap upon the base so that both may be 105 fired at the same time, and utilize the same space in the saggar during such firing, the following arrangement is employed: As will be best noted upon reference to Figs. 1 and 4, the upper face of the base is pro- 110

vided with two small "stick-ups" or projections 13, which are located adjacent the grooves. The upper face, intermediate the grooves and adjacent each end thereof, is 5 cut away or depressed slightly, as at 14, so that said cut-away portions are of substantially the same height as the other parts of the face 2. When the cap is placed upon the base, after being formed, and as the 10 parts are put in the sagger, the stick-ups 13 will contact with the ribs 9 and hold the parts separated or out of contact throughout, with the exception of the contact between the stick-ups and the ribs. By having 15 the upper face cut away, as at 14, and providing the stick-ups, the depending flange or rim 8 is, during the firing operation, kept out of contact with the underlying base, and consequently when the parts 20 are separated after firing the rim remains intact and the only points which have to be broken away are those which obtain between the upper end of the stick-ups and the contacting ribs.

25 The construction above outlined admits of the ready placement of the wires, and insures their retention in place. The depending flange or rim 8, the radially-disposed ribs 9, and the transverse ribs 5 bite into 30 the wires or the insulation thereof and firmly hold the wires against movement. The angular disposition of the ribs effectively grips the wire and any pull or strain exerted on the wire tends to crowd the same 35 laterally and cause it to more firmly hug the wall of the groove 4 through which it extends.

It is likewise to be noted that the depending flange 8 and the ribs 9 both overlie and 40 contact with the wire which is placed in the grooves 4. The depending flange 8 contacts with the wire adjacent each end of the groove and such portion of the flange stands at an angle to the ribs 5 and also the ribs 45 9, and furthermore, such contacting portions of the flange 8 stand at an angle to each other. Thus the upper face of the wire is in contact with the angularly-disposed ribs 9, and the depending portions 50 of the flange 8 which, as just noted, stand at an angle to each other and to said ribs 9. Furthermore, the ribs 5 stand at an angle to the overlying ribs 9 and the depending flange 8. There is thus produced a number 55 of lines of contact extending across the wire, particularly the upper portion thereof, which are angularly disposed to each other and all of which have a tendency to hold the wire firmly in place without any undue strain thereon.

60 It will, of course, be appreciated, that a greater number of ribs 9 than those shown may be employed, that being a mere matter of degree and falling within the scope of my invention.

Having thus described my invention, what I claim is:

1. An insulator, comprising in combination a body, and a cap-piece provided with alining bores, the body at its upper end 70 being formed with a wire-receiving groove having a series of transverse ribs extending upwardly from the bottom thereof and likewise provided with a lug or teat extending outwardly from the upper face of the body, 75 and said cap piece being provided with a centrally-disposed socket to receive the lug or teat and likewise with a series of radially-disposed ribs formed upon the under face of the cap, the ribs extending outwardly to 80 a point adjacent the periphery of the cap and overlying the groove, said ribs being of a depth such that they project downwardly to substantially the under plane of the cap and contact with the wire which is 85 placed within the groove and force the wire into contact with the ribs in the groove without bending the wire.

2. An insulator, comprising in combination a body, the upper end of said body 90 being formed with an upwardly-projecting lug and having a pair of grooves formed in said upper end on opposite sides of the lug, said grooves having cross ribs formed therein; and a cap-piece, said cap-piece upon its under face being formed with a central socket to receive the lug aforesaid and likewise having a series of radially-disposed ribs upon its under face which terminate at their outer ends in a downwardly-extending circumferential flange, the ribs and flange being of a substantially equal depth and adapted to impinge against the wires laid within the grooves without bending the same, the body and cap piece being provided with alining bores.

3. An insulator, comprising in combination a cylindrical body portion having two grooves extending across the upper face thereof, a series of ribs extending transversely across the bottom of each groove, and a teat projecting upwardly from the face intermediate the grooves; and a cap-piece having a narrow depending circumferential rim formed thereon, and a series of 110 radially-disposed ribs extending inwardly from the flange, said ribs and flange being of substantially equal depth and said ribs terminating at their inner ends in line with the wall of a socket formed centrally in the 115 lower face of the cap and adapted to receive the teat aforesaid and to thereby center the cap upon the body portion, said cap and body portion being likewise provided with alining bores.

4. An insulator, comprising in combination a body; and a cap-piece provided with alining bores, the body at its upper end being formed with wire-receiving grooves having a series of transverse ribs extending 120

upwardly from the bottom thereof and likewise provided with a lug or teat extending upwardly from the upper face of the body and also with a plurality of stick-ups extending 5 upwardly from the upper face of the body, and said cap-piece being provided with a centrally-disposed socket to receive the lug or teat and likewise with a series of radially-disposed ribs formed upon the under face 10 of the cap, the ribs extending downwardly to a point adjacent the periphery of the cap and overlying the grooves, said ribs being of such depth as to contact with the wires when placed within the grooves.

15 5. An insulator, comprising in combination a body; and a cap-piece provided with alining bores; the body at its upper end being formed with a wire-receiving groove and a plurality of stick-ups projecting upwardly beyond the plane of the upper face 20 of the body, and said cap-piece being provided with means upon its under face to coöperate with the groove to secure a wire in place between them, said cap piece likewise contacting with the stick-ups, and normally holding said means out of contact with the underlying body.

In testimony whereof I have signed my name to this specification.

FRANK AMOS.
